UNITED STATES PATENT OFFICE.

FREDERICK M. VENZIE, OF PHILADELPHIA, PENNSYLVANIA.

BUILDING CONSTRUCTION.

Application filed February 5, 1925. Serial No. 6,966.

This invention, stated in general terms, relates to building construction, particularly floors and ceiling structures of concrete. In work of this character great difficulty is experienced with the labor problem. Not only must skilled labor be employed but the expense incident thereto is almost prohibitive. According to the present invention I propose to employ structural parts which may be readily assembled by unskilled labor thus first eliminating the need for skilled labor and second, bringing building costs nearer normal, the advantages of which are readily apparent.

15 The invention consists of the novel construction hereinafter described and finally claimed.

The nature, characteristic features and scope of the invention will be more fully understood from the following description taken in connection with the accompanying drawings forming part hereof, and in which:

Fig. 1, is a view in section of a floor and ceiling structure embodying the invention.

25 Fig. 2, is a top or plan view of Fig. 1, with certain parts removed for clearer illustration.

Fig. 3, is a fragmentary view in section taken approximately upon the line 3—3 of Fig. 2.

30 Fig. 4, is a fragmentary view taken upon the line 4—4 of Fig. 1.

Fig. 5, is an elevational view of Fig. 4.

Fig. 6, is a view of the cross-braces shown in Figs. 4 and 5 in detached relation.

35 Fig. 7, is a fragmentary view in section of the extreme end portion of an upper beam.

Fig. 8, is a view in section taken upon the line 8—8 of Fig. 1.

40 Fig. 9, is a face view of the clip shown in Fig. 8, and

Fig. 10, is an edge view of Fig. 9.

For the purpose of illustrating my invention I have shown in the accompanying drawings one form thereof which is at present preferred by me, since the same has been

45 found in practice to give satisfactory and reliable results, although it is to be understood that the various instrumentalities of

50 which my invention consists can be variously arranged and organized and that my invention is not limited to the precise arrangement and organization of the instrumentalities as herein shown and described.

55 Referring now to the drawings in detail,

the numeral 11 designates lateral I-beams spaced apart and spanned by longitudinal beams which rest upon the tops of the I-beams. These beams are made of angle irons 12—13 bolted together at 14 to form T-shaped beams see Fig. 3. Spaced below the upper or longitudinal beams are other or lower longitudinal beams each made up of angle irons 15—16 bolted together at 17 to 60 form inverted T-shaped beams. These lower beams are suspended from and supported by the upper beams by spaced vertical struts each made up of angle irons 18—19. The tops and bottoms of these struts are bent 65 horizontally as at 20—21, and bolted as at 22 to the upper and lower longitudinal beams. In order to add strength and rigidity to this arrangement of beams tie-rods 23—24 are provided. Each of the tie-rods 70 is bent U-fashion so as to straddle the upper longitudinal beam and the vertical struts and the adjacent ends of the opposing tie-rods are connected by turn-buckles 25. The longitudinal upper beams and struts are 75 each notched to accommodate the tie-rods. Upon the upper beams is laid sheet iron 26, see Fig. 2. At suitable intervals upon said sheet iron are positioned brackets of thin metal. These brackets are formed of two 80 pieces 27—28 arranged X-fashion. The separated parts are seen in Fig. 6, each part being notched as at 29 so that they may be fitted properly together and the edges may be notched as at 30 and the ends provided with 85 prongs 31. Supported by said brackets are sheets of heavy wire mesh designated 32. The prongs 31 of the brackets are used to clamp over the wire mesh and the notches 30 afford resting portions to receive the wire 90 mesh, said brackets being reversible in character for this purpose. Positioned upon said brackets are a plurality of wooden sleepers 95 designated 33 which parallel the I-beams 11. These sleepers are secured with respect 100 to the upper beams and brackets by means of clips of metal, best seen in Figs. 4 and 5. The clips are designated 34 and are passed up between the space 35 between the upper beam sections 12—13. The lower end 105 of each clip is bent over upon the web of one of said beam sections as at 36 and the upper end of each clip is bent over a sleeper 33 as at 37. Other clips 38, are provided to retain blocks 43 in place. With the above 110 described parts in position concrete is poured around the sleepers and brackets

and through the wire mesh and upon the sheet metal plates as best seen in Fig. 1. Flooring 39 is then laid to complete the floor structure.

- 5 Taking up now the ceiling structure, the same is supported from the lower beams. Clips, best seen in Figs. 9 and 10, are passed up between the sections 15—16 of the lower beams and the upper ends 41 bent over the 10 upper edges of said beam sections so as to have the lateral flanges 40 of the clips abut against the underside of the beam sections 15—16. Ceiling blocks 43, as of plaster or other material, are then positioned below the 15 beam sections 15—16 and the lower forks 41'—41' of the said clips are bent over laterally beneath adjacent ends of a pair of blocks 43, see Fig. 8, and the pointed ends of said prongs forced up into the blocks 43. 20 Staples 44 may be employed to retain the fork-ends 41' in engagement with said blocks. Plaster or finishing material 42 is then applied to the under side of the blocks and concrete may be poured around the 25 lower portions of the beam sections 15—16 as shown.

Referring now specifically to Fig. 7, the extreme ends of the upper beams are reinforced by angle plates 45—46, parts of which 30 are fitted between the beam parts and bolted as at 47. One end 48 of each of these plates is bent over the upper beam end, see Fig. 1, and the opposite end 50 is secured as by bolts 51 to a strut 19. These struts 19 are tied 35 together by rods 52 hooked through apertures 53 in said struts.

It will now be apparent that I have devised a novel and useful construction which embodies the features of advantage enumerated as desirable in the statement of the 40 invention and the above description and while I have in the present instance shown and described the preferred embodiment thereof which has been found in practice to give 45 satisfactory and reliable results, it is to be understood that the same is susceptible of modification in various particulars without departing from the spirit or scope of the invention or sacrificing any of its advantages.

What I claim is:

1. A structure of the character stated comprising spaced I-beams having suspended therebetween and therefrom upper and lower 55 horizontal beams of angle iron connected by

vertical struts also of angle iron, tie-rods including turnbuckles connecting the ends of the upper of said beams, metal plates upon said upper beams, X-shaped brackets spaced upon said plates, wire mesh supported by the brackets, sleepers paralleling the I-beams supported by the brackets, a fill of concrete around said sleepers and brackets and flooring upon said sleepers. 60

2. A structure of the character stated comprising spaced I-beams having suspended therebetween and therefrom upper and lower horizontal beams of angle iron connected by vertical struts also of angle iron, tie-rods including turnbuckles connecting the ends 70 of the upper of said beams, metal plates upon said upper beams, X-shaped brackets spaced upon said plates, wire mesh supported by the brackets, sleepers paralleling the I-beams supported by the brackets, clips for securing said sleepers with respect to said upper beams, a fill of concrete around said sleepers and brackets and flooring upon said sleepers. 75

3. A structure of the character stated comprising spaced I-beams having suspended therebetween and therefrom upper and lower horizontal beams of angle iron connected by vertical struts also of angle iron, tie-rods including turnbuckles connecting 80 the ends of the upper of said beams, metal plates upon said upper beams, X-shaped brackets spaced upon said plates, wire mesh supported by the brackets, sleepers paralleling the I-beams supported by the brackets, clips for securing said brackets with respect to said upper beams, a fill of concrete around said sleepers and brackets and flooring upon said sleepers. 85

4. A structure of the character stated comprising spaced I-beams having suspended therebetween and therefrom upper and lower horizontal beams of angle iron connected by vertical struts also of angle iron, tie-rods including turnbuckles connecting the ends 90 of the upper of said beams, ceiling blocks, clips having lateral flanges abutting against the underside of the lower beam and having their tops bent over said lower beam and their lower parts bent against the bottoms of said blocks and a plaster surfacing covering said clip bottoms. 95

In testimony whereof, I have hereunto signed my name.

FREDERICK M. VENZIE.
